CORE CATCHER

John C. Stokes, Houston, Tex., assignor to Reed
Roller Bit Company, Houston, Tex., a corpora-
tion of Texas

Application August 19, 1946, Serial No. 691,639

8 Claims. (Cl. 255—72)

1

This invention relates to core catchers and will be found particularly useful in deep well core drills.

It has for one of its general objects the provision of a new and improved method whereby core catchers may be manufactured at a substantially lower cost, and a new and improved core catcher which will efficiently perform its function in operation and which may be readily and cheaply repaired in the event any of its parts are damaged or destroyed.

Other objects of the invention will hereinafter appear.

The preferred embodiment of the invention is illustrated by the accompanying drawings in which Fig. 1 is a sectional elevation of the lower end of a deep well core drill with the catcher therein in its upper inactive position; Fig. 2, a view similar to Fig. 1 with the catcher in its lower active position; Fig. 3, a sectional elevation of the core catcher; Fig. 4, a horizontal section on the line 4—4 of Fig. 3; and Figs. 5, 6, and 7 are views illustrating the manufacture of the spring finger from a metallic strip.

Referring to Fig. 1, the numeral 1 indicates the conventional deep well drill stem and the numeral 2 a conventional bit threaded on the lower end thereof.

The bit 2 is hollow to receive the core cut by the cutting teeth 3 and it has an internal downwardly tapered seat 4. Within the bit 2 and cooperating with the seat 4 is the new and improved core catcher provided by this invention.

The core catcher is illustrated in detail by Fig. 3. It includes a ring 5 which is slidable up and down in the bit head 2 and has depending therefrom circumferentially spaced spring fingers 6. The ring 5 has internal circumferentially spaced recesses 7 to receive the upper ends of the spring fingers 6 and said fingers are riveted in said recesses as indicated at 8. The spring fingers may be made of a higher carbon steel than the ring 5 to which they are thus attached.

The lower ends of the spring fingers 6 are bent inwardly, as indicated at 6a to slide inwardly on the seat 4 of the bit head 2, as indicated in Figs. 1 and 2. The bent portions 6a of the spring fingers have claws 6b extending inwardly from opposite sides of said bent portions to engage a hard core when the catcher is in the position shown by Fig. 2. The spring fingers 6 may, therefore, be referred to as the hard formation spring fingers.

Riveted as indicated at 9 to the hard formation spring fingers 6 and extending upwardly and

2

inwardly to engage the core are soft formation spring fingers 10. These soft formation spring fingers 10 are mounted on every other one of the hard formation spring fingers 6 as shown, and they function not only to retain a soft formation core in the core catcher but also to cause the core catcher to move downwardly upon the seat 4 and thereby bring the claws 6b into engagement with the hard formation core when the drill stem is pulled upwardly.

Referring to Figs. 5, 6, and 7, the hard formation core fingers are made by stamping the spring finger shown by Fig. 6 from the metal strip 5 and then bending the wing portions 6b' inwardly through substantially 90 degrees to form the spaced claws 6b.

It will be apparent to those skilled in the art that the method of making this core catcher reduces machining to a minimum, and that when 20 made the core catcher will efficiently perform its function and that its parts may be readily replaced when damaged or destroyed.

It will be understood that the spring fingers 6 and 10 have been referred to as the hard formation and soft formation spring fingers, respectively, for convenience in description.

The invention is not limited to the preferred embodiment disclosed. Various changes will occur to those skilled in the art, within the scope 30 of the following claims.

I claim:

1. A core drill including a hollow head having an internal downwardly tapered seat, and a core catcher in said head, said catcher including a 35 ring slidable axially in said head and having circumferentially spaced recesses, circumferentially spaced hard formation spring fingers riveted in said recesses and extending downwardly and having inwardly bent lower portions to slide 40 inwardly on said seat upon downward movement of said catcher, said bent portions having claws extending inwardly from opposite sides of said bent portions to engage a core, and soft formation spring fingers riveted to said hard formation 45 fingers at positions spaced from said ring and extending upwardly and inwardly to engage a core.

2. A core drill including a hollow head having an internal downwardly tapered seat, and a core catcher in said head, said catcher including a ring slidable axially in said head and having circumferentially spaced recesses, and circumferentially spaced spring fingers riveted in said recesses and extending downwardly and having inwardly bent lower portions to slide inwardly on

said seat upon downward movement of said catcher, the bent portion of each finger having spaced claws extending inwardly from opposite longitudinal edges of said bent portions to engage a core.

3. A core catcher including a ring having circumferentially spaced recesses, circumferentially spaced hard formation spring fingers riveted in said recesses and extending downwardly and having inwardly bent lower portions, said bent portions having claws extending inwardly from opposite sides of said bent portions to engage a core, and soft formation spring fingers riveted to said hard formation fingers at positions spaced from said ring and extending upwardly and inwardly to engage a core.

4. A core catcher including a ring, and circumferentially spaced spring fingers riveted to said ring and extending downwardly and having integral inwardly bent lower portions, said bent portions having integral laterally spaced claws extending inwardly from opposite longitudinal edges of said bent portions to engage a core.

5. A core catcher including a ring, circumferentially spaced spring fingers joined to and depending from said ring, and soft formation core catcher spring fingers secured to said first spring fingers at positions spaced from said ring and extending back along said first fingers toward the ring and inwardly toward the axis of the ring.

6. A core catcher including a ring, circumferentially spaced spring fingers joined to and depending from said ring, and having integral inwardly bent lower portions, the bent portion of each finger having integral laterally spaced claws extending inwardly from opposite longitudinal edges of said bent portions to engage a core.

7. A core catcher including a ring, circumferentially spaced spring fingers joined to and depending from said ring, and having integral inwardly bent lower portions, said bent portions having integral laterally spaced claws extending inwardly from opposite sides of said bent portions to engage a core, and soft formation core catcher spring fingers secured to said first spring fingers at positions spaced from said ring and adjacent said inwardly bent portions of said first fingers and extending back along said first fingers toward the ring and inwardly toward the axis of the ring.

8. A core catcher including a ring, circumferentially spaced spring fingers joined to and depending from said ring, and having integral inwardly bent lower portions, and soft formation core catcher spring fingers secured to said first spring fingers at positions spaced from said ring and adjacent said inwardly bent portions of said first fingers and extending back along said first fingers toward the ring and inwardly toward the axis of the ring.

JOHN C. STOKES.
